UNITED STATES PATENT OFFICE.

WALTER H. COTTON, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,204,948.

Specification of Letters Patent.

Patented Nov. 14, 1916.

Application filed August 23, 1915. Serial No. 48,951.

To all whom it may concern:

Be it known that I, WALTER H. COTTON, a citizen of the United States, and resident of Chicago, county of Cook, and State of Illinois, have invented certain new and useful Improvements in Draft-Gear, of which the following is a specification, and which are illustrated in the accompanying drawings, forming a part thereof.

The invention relates to draft gears of the general type shown in Patent No. 989,949, granted to Walter H. Cotton and Thomas D. Henderson April 18th, 1911. Its objects are to generally improve upon gears of this type, and particularly to provide for distributing the pressure, due to the wedging action, upon the casing which incloses the friction elements, and to increase the efficiency of the friction plates in absorbing the pressure.

One embodiment of the invention is hereinafter described, and is illustrated in the accompanying drawings, in which—

Figure 1 is a central vertical section through the gear, showing it as applied to a car, the coupler and its extension and the draft sills being shown in elevation; Fig. 2 is a plan view, partly in section, of the gear as applied to a car and showing the gear under draft compression; Fig. 3 is a central plan section of the gear as applied to the car, the gear being shown in release position; Fig. 4 is a rear end view of the gear; Fig. 5 is a detail section on the line 5—5 of Fig. 4; Fig. 6 is a side view of one of the outer wedging elements; and Fig. 7 is a side view of the central wedging element.

The draft sills of a car are shown at 10, 10, the draft and buffing lugs being represented, respectively, at 11, 12. At 13 there is shown the butt of a coupler, and at 14 a yoke or coupler extension. These parts may all be of any desired construction.

The gear comprises a shell or casing 15, one end, 16, of which is substantially closed and may constitute a follower for engaging the draft lugs 11 and a seat for the springs 17, 18, which are nested and have identical functions. Seated against the inner end

of the springs is a follower 19, which may be an imperforate plate. A follower plate 20, seated against the inner end of the yoke 14, co-operates with the buffing lugs 12, and is engageable with the inner end of the casing 15 when the gear reaches the limit of its compressive movement.

Interposed between the followers 19 and 20 are a plurality of co-operating wedging elements, the inner element, 21, being in constant engagement with the follower 20, and the outer wedging elements 22, 23, being in constant engagement with the follower 19. The several wedging elements are substantially U-shaped, the element 21 comprising a cross-head 24 and a pair of legs 25, 26, upon which are formed the wedging faces, the legs being united by a web 27. Each of the wedging elements 22, 23, comprises a cross-head 28, and a pair of legs 29, 30, upon which are formed the wedging faces co-operating with such faces on the element 21. The cross-head 24 of the wedging element 21 is provided with laterally projecting flanges 31, 32, forming spring seats, and the cross-head of each of the elements 22, 23, is provided with an outstanding flange 33, these several flanges constituting seats for the releasing springs 34, 35.

Located on each side of the several wedging elements there is a series of friction plates, segmental in form in cross-section, the entire series constituting an arch, the periphery of which bears against the inner surface of the wall of the casing. Each group of friction plates is composed of two sets, the members of which alternate. One set of these plates, 36, is considerably shorter than the other set 37. The shorter plates 36 are held against longitudinal movement with reference to the casing by means of outstanding lugs 38, entering suitable apertures in the wall of the casing. If desired some or all of these apertures may be spanned by bridges 39, as shown in Fig. 5, for the purpose of increasing the strength of the casing. The other set of plates, 37, is free to move or float longitudinally.

While the expansion of the wedging ele-

ments, due to their relative advance movement, forces the two arched groups of friction plates laterally against the casing, much of this outward pressure is absorbed within 5 the arch itself, which is compressed from each end toward its central or key element and consequently the shell, being relieved of much of the wedging stress, may be comparatively light, and especially as all of 10 the expansive pressure is arrested by the shell in tension.

When the gear is in release position, as shown in Figs. 1 and 3, the plates 37 project beyond the end of the casing but do 15 not reach the follower 20. Under draft stresses the follower 20 is moved forward, ultimately to the position shown in Fig. 2. Its initial movement causes the advance of 20 the wedging element 21 against the resistance of the springs 34, 35, which are much weaker than the springs 17, 18. The wedging elements 22, 23, are thereby forced outwardly, compressing the two friction plate arches and increasing the friction between 25 the elements thereof. As the several friction plates normally fit closely together the expansive movement of the wedging elements is but slight, and when its limit is reached the three wedging elements move 30 together, compressing the springs 17, 18. When the follower 20 comes into engagement with the floating plates 37, the latter are carried forwardly with it, sliding frictionally upon the plates 36, the friction developed being sufficient to absorb in great 35 measure the draft stresses, and being gradually augmented by the increased resistance of the springs as the latter are compressed. When the pull upon the coupler ceases the 40 parts of the gear are returned to their original positions by the springs 17, 18. The springs 34, 35, act promptly to relieve the wedging action, but a violent recoil is prevented by the action of the springs 17, 18, 45 in causing the outer wedging elements 22, 23, to follow up the central element 21, thereby insuring a gradual diminution of frictional resistance. The action of the gear under the influence of buffing stresses is simply 50 the reverse of that which takes place in draft, the casing and its contents being moved inwardly toward the follower 20.

I claim as my invention—

1. In a draft gear, in combination, a casing, a spring within the casing seated against a suitable shoulder thereon, a follower engaging the opposite end of the spring, a follower beyond the end of the casing, a set of wedging elements bearing, 55 respectively, on the two followers, two groups of segmental friction plates, each group being arranged in arch form, the arch springing at each end from a wedging element, alternate plates being anchored

against longitudinal movement with reference to the casing and alternate plates being longitudinally movable with reference thereto. 65

2. In a draft gear, in combination, a casing, a spring within the casing seated against a suitable shoulder thereon, a follower engaging the opposite end of the spring, a follower beyond the end of the casing, a set of wedging elements bearing, respectively, on the two followers, two groups of segmental friction plates, each group being arranged in arch form, the arch springing at each end from a wedging element, alternate plates being anchored against longitudinal movement with reference to the casing and alternate plates being longitudinally movable with reference thereto, and a spring reacting longitudinally between the two wedging elements. 70 80

3. In a draft gear, in combination, a casing, a spring within the casing seated against a suitable shoulder thereon, a follower engaging the opposite end of the spring, a follower beyond the end of the casing, a central U-shaped wedging element 90 having wedging faces on its legs and flanges projecting laterally from its cross member, a pair of U-shaped wedging elements co-operating therewith and each having a flange projecting laterally from its cross members, such co-operating wedging elements being respectively seated against the two named followers, two groups of segmental friction plates, each group being arranged in arch form, the arch springing at 95 each end from a wedging element, alternate plates being anchored against longitudinal movement with reference to the casing and alternate plates being longitudinally movable with reference thereto, and springs reacting upon the lateral flanges of the co-operating wedging elements. 100 105

4. In a draft gear, in combination, two groups of segmental friction plates, each group arranged in arch form and alternate plates being relatively longitudinally movable, and wedging means acting on the ends of the arches, the spreading action of the wedge elements being due to their relative movement in the line of draft. 110 115

5. In a draft gear, in combination, two sets of intercalated relatively movable friction plates arranged in arch form, and means acting compressively on the ends of the arches, such action being due to the movement of said means parallel to the line of draft. 120

6. In a draft gear, in combination, intercalating friction plates, co-operating wedge elements for pressing the plates together, a spring reacting between the wedge elements to relieve the wedging action and a spring acting on one of the wedging elements in 125

opposition to the first-named spring for retarding the release.

7. In a draft gear, in combination, a casing, a cross section thereof forming an oblong figure with symmetrically curved ends and parallel sides, two groups of intercalated relatively movable friction elements, each group being arranged in arch form and located within one of the named curved portions of the casing, and wedging means acting on the ends of the arches. 10
